United States Patent Office.

HENRY AXTELL, OF YREKA, CALIFORNIA.

Letters Patent No. 92,507, dated July 13, 1869.

IMPROVED WIRE-CUTTER.

The Schedule referred to in these Letters Patent and making part of the same.

To all whom it may concern:

Be it known that I, HENRY AXTELL, of Yreka, in the county of Siskiyou, and State of California, have invented a new and useful Improvement in Wire-Cutter; and I do hereby declare that the following is a full, clear, and exact description thereof, which will enable others skilled in the art to make and use the same, reference being had to the accompanying drawings, forming part of this specification.

This invention relates to a new and improved implement for cutting wire or bolt-iron of the smaller sizes, whereby much time and labor are saved; and

It consists in constructing the handles or parts which are pivoted together, with cutting-edges arranged eccentrically to each other, and on a line with the side of the tool, as will be hereinafter more fully described.

In the accompanying plate of drawings—

Figure 1 represents a longitudinal side view of the tool, showing the cutting-edges and the manner of construction.

Figure 2 is an edge view of the same.

Similar letters of reference indicate corresponding parts.

This implement or tool is formed of two parts, A and B, connected together by a rivet or bolt, C.

It will be seen that these two parts A and B act as levers, C being the fulcrum, with the cutting-edges formed on the short ends of the levers.

d is the cutting-edge of the part A, and e is the cutting-edge of part B.

These edges are so formed and arranged (in relation to each other) that they work eccentrically to each other.

The distance of the cutting-edges from the fulcrum C is so short, as compared with the long end of the levers, that great power is applied to any resisting medium, as wire and the smaller sizes of round or other iron, or other metals, as copper or brass.

To render the tool strong and durable, the part B is slotted for receiving the part A, so that the fulcrum-pin or bolt C is supported at both ends, as seen in fig. 2.

This tool is particularly adapted (when made of proper size and strength) to cut off the ends of bolts in carriage-making and other similar work, as well as rivets in a fixed position, as it will be seen that the cutting-edges are on a line with the side of the tool.

These tools may be made of any desired size, thus adapting them to use in blacksmith-shops for cutting up small iron, for cutting off the ends of bolts in carriage-making, and all description of machinery, and for a great variety of purposes, as must be obvious to all.

Having thus described my invention, I claim as new, and desire to secure by Letters Patent—

The improved wire-cutter, constructed, as described, of the pivoted parts A B, provided respectively with the cutting-edges d e, arranged eccentrically to each other, and on a line with the side of the tool, as herein described for the purpose specified.

HENRY AXTELL.
